TRACK FRAME STABILIZER FOR TRACK-LAYING TRACTORS

Edward A. Johnston, Chicago, Ill., assignor to
International Harvester Company, a corporation of New Jersey

Application May 6, 1932, Serial No. 609,651

5 Claims. (Cl. 305—9)

This invention relates to track frame stabilizers for track-laying tractors.

The principal object of the invention is to provide a flexible, track-laying tractor with means for maintaining the tracks against lateral movement with respect to each other and with respect to the main frame of the tractor. This object is accomplished by providing stabilizing means connected to the forward ends of the track frames 5 and to the main frame of the tractor, said means being constructed to permit up-and-down movement of the track frames and to prevent movement of the track frames in a lateral direction with respect to the main frame of the tractor.

15 In the drawings:

Figure 1 is a general plan view of a tractor chassis embodying the invention with certain parts broken away and other parts removed to more clearly illustrate the invention;

20 Figure 2 is a side elevation of the same structure shown in Figure 1;

Figure 3 is a sectional view taken on the line 3—3 of Figure 1;

25 Figure 4 is an enlarged detail of the connection between the stabilizing member and the main frame of the tractor;

Figure 5 is a section taken on the line 5—5 of Figure 4; and

30 Figure 6 is a section taken on the line 6—6 of Figure 4.

Referring to the drawings, the main frame 10 of the tractor is of a conventional construction except for the addition of the securing means for the stabilizer, to be hereinafter described. Driving means for the track 11 are provided at the rear of the tractor, said means being of any conventional construction. The track frames 12, positioned at the sides of the tractor, are pivoted to the main frame on a transverse axis. This 35 construction has not been shown in detail as it is well known in the art. The axis of attachment is designated by the numeral 13. The front equalizer support 14 in the form of a spring, extends under the forward portion of the main frame and over the track frames. Said support is pivotally connected on a longitudinal axis to the main frame, as shown in Figure 3. Said support is also pivotally connected to the track frames by means enclosed in the housings 15 secured to the track frames. The particular construction of the housing 15 and the attaching means therein, is the subject-matter of the co-pending application, Serial No. 578,429 filed December 2, 1931.

55 It is to be understood that the construction above described is well known in the art and it is in connection with a track-laying tractor of the type described that the stabilizer of the present invention is to be applied.

60 In the operation of a tractor of this type, the

track frames at the sides of the main frame move up and down with respect to each other and with respect to the main frame, the support 14 serving as an equalizer. By reason of the pivotal arrangement of said equalizer member, the upward 5 pivotal movement of one of the track frames 12 will produce a corresponding downward movement on the opposite track frame. In other words, the track frames will be able to accommodate themselves to the varying character of the 10 road upon which they are traveling without disturbing the position or equilibrium of the main frame or body of the tractor. It is necessary that the ends of the support be connected to the track frame by means which will permit lateral movement 15 of the track frames with respect to the ends of the support. This is necessary because, as the spring rotates about its axis of attachment with the main frame, the lateral horizontal distance between its ends shortens. This movement 20 has been provided for in numerous ways, such as by spring shackles of different types. In the particular embodiment of the invention illustrated, said movement is provided for by pivotally connecting the ends of the transverse support 14 25 on cylindrical attaching members 16, as shown in Figure 6. Said members are arranged with their axes extending in transverse directions. The cylindrical attaching members are mounted in the housings 15 for limited lateral movement 30 therein, whereby the necessary lateral movement of the ends of the support 14 with respect to the track frames, is obtained.

A member 17, consisting of a body portion and two parallel and oppositely extending stub shafts 35 18 and 19, is positioned at each side of the tractor to form the stabilizer connection between the main frame and the track frame. The members are exactly similar in construction except that one is left-handed with respect to the other. The 40 shaft 19 rotatably extends through a bearing member 20 mounted on the track frame. Said shaft is provided with a shoulder 21 at its inner end of the bearing 20 and a thrust element 22 at the outer end to prevent lateral movement of the 45 shaft and the member 17 with respect to the track frame.

The member 17 extends in a substantially horizontal position when the track frames are on the same level, as shown in Figure 2. The shaft 18 50 is positioned on the member 17 forwardly from the shaft 19.

Below the main frame at each side an integral boss or supporting bracket 23 is formed with a vertical face for attaching a housing 24. Said 55 housing has a cover plate 25 secured thereto and is formed internally with two parallel spaced walls arranged in vertical longitudinally extending planes, one of said walls being the inner surface of the cover plate 25. As best shown in Figure 5, 60

said cover plate is provided with a substantially centrally located opening in the form of a slot 26 extending in the longitudinal direction. The shaft 18 extends through the opening, said opening being slightly larger in the vertical dimension than the diameter of the shaft, and considerably longer in the fore and aft direction. A plate 27 is rigidly secured to the end of the shaft 18 and is mounted within the housing 24. Said plate is cylindrical in form and is of a thickness slightly less than the width of the space formed by the inner walls of the housing. The plate is also somewhat less in diameter than the diameter of the interior of the housing, whereby it may move freely within the limits defined by the interior of the housing. A flexible shield 28 is secured to the plate 25 around the slot 26 and around the shaft 18 to form an oil-tight seal between said members while permitting rotation of the shaft with respect to the housing and the fore and aft movement of translation.

By the construction above described, it will be understood that upon pivoting movement of the track frame 12 with respect to the main frame 10 of the tractor the bearing member 20 carried on the track frame will move up and down, thereby lifting and lowering the shaft 19 and the rear end of the stabilizing member 17. Said member will also be angularly moved with respect to the main frame, its movement being permitted by rotation of the plate 27 within the housing 24. It will also be understood that due to the fact that the track frame 12 and the member 17 are pivoted on different axes on the main frame, it will be necessary for one of the axes to move with respect to the other as the common axis, that is, the axis of the shaft 19 moves up and down. This movement is provided for by the slot 26, which is of a length sufficient to allow the fore and aft movement of the shaft 18 for the maximum angular displacement of the track frame. There is also sufficient clearance between the interior walls of the housing and the plate 27 to permit the fore and aft movement of translation required by said angular movement of the track frame with respect to the main frame. The shield 28 encloses the moving parts in such a manner that dust cannot enter and lubrication will not be affected. As the plate 27 cannot move laterally with respect to its housing and as the shaft 19 cannot move laterally with respect to the bearing member 20 on the track frame, the stabilizer member 17 prevents lateral movement of the track frame with respect to the main frame. The comparatively long length of the bearing 20 and the large area of the plate 27 give the stabilizing member sufficient strength to resist all side thrusts encountered in normal operation.

It is to be understood that applicant has shown and described only a preferred embodiment of his improved stabilizing means for track-laying tractors and that he claims as his invention all modifications falling within the scope of the appended claims.

65 What is claimed is:

1. In a track-laying tractor having a main frame, track frames pivotally connected on a transverse axis to the rear of the main frame and a transverse front support pivotally connected to the main frame and to the track frames, a track stabilizer at each side of the tractor consisting of a single connecting member, means for connecting said member to a track frame on a transverse axis, and means for directly con-

necting the member to the main frame for angular movement with respect thereto on a transverse axis and for limited movements of translation in the fore and aft directions.

2. In a track-laying tractor having a main frame, track frames pivotally connected on a transverse axis to the rear of the main frame, and a transverse front support pivotally connected to the main frame and to the track frames, a track stabilizer at each side of the tractor consisting of a single member having spaced oppositely extending stub shafts, one of said shafts being pivoted on a track frame on a transverse axis, and means for connecting the other shaft directly to the main frame for angular movement with respect thereto on a transverse axis and for limited movement of translation in the fore and aft directions.

3. In a track-laying tractor having a main frame, track frames pivotally connected on a transverse axis to the rear of the main frame, and a transverse front support pivotally connected to the main frame and to the track frames, a track frame stabilizer at each side of the tractor comprising a member having spaced oppositely extending stub shafts, one of said shafts being pivoted on a track frame on a transverse axis, and means for connecting the other shaft to the main frame for angular movement with respect thereto and for limited movement of translation in the fore and aft directions, said means consisting of a plate fixed to the end of the shaft in a substantially longitudinal vertical plane and means on the main frame to hold said plate for rotation with respect thereto and to permit limited longitudinal movement of the plate.

4. In a track-laying tractor having a main frame, track frames pivotally connected on a transverse axis to the rear of the main frame, and a transverse front support pivotally connected to the main frame and to the track frames, a track frame stabilizer at each side of the tractor comprising a member having spaced oppositely extending stub shafts, one of said shafts being pivoted on a track frame on a transverse axis, and means for connecting the other shaft to the main frame for angular movement with respect thereto and for limited movement of translation in the fore and aft directions, said means consisting of a housing secured to the main frame, a cover plate on said housing formed with an opening in the form of a longitudinally extending slot through which the shaft extends, a plate fixed to the end of the shaft within the housing for angular movement with respect thereto and for limited movement of translation in a longitudinal vertical plane.

5. In a track-laying tractor having a main frame, track frames pivotally connected on a transverse axis to the rear of the main frame and a transverse front support pivotally connected to the main frame and to the track frames, a track stabilizer at each side of the tractor comprising a connecting member between the main frame and one of the track frames, means for pivotally connecting said member to one of the frames which it connects for angular movement with respect thereto on a transverse axis, and means for directly connecting the member to the other of said frames for angular movement with respect thereto on a transverse axis and for limited movements of translation in fore and aft directions.

EDWARD A. JOHNSTON.
